(57) **CLAIM**

The ornamental design for a swinger gladhand, as shown and
described.

DESCRIPTION

FIG. 1 is a front left, perspective view of a swinger gladhand;
FIG. 2 is a front right, perspective view of the swinger gladhand;

FIG. 3 is a front plan view of the swinger gladhand;
FIG. 4 is a top plan view of the swinger gladhand;
FIG. 5 is a bottom plan view of the swinger gladhand;
FIG. 6 is a right elevational view of the swinger gladhand;
FIG. 7 is a left elevational view of the swinger gladhand; and,
FIG. 8 is a rear elevational view of the swinger gladhand.
The broken line showings in the accompanying drawings are
for illustrative purposes only and forms no part of the claimed
design.
